(57) CLAIM

The ornamental design for a hanger for clothing care machine as shown and described.

DESCRIPTION

FIG. 1 is a top, front and right-side perspective view of a hanger for clothing care machine showing our new design; FIG. 2 is a bottom, rear and left-side perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a partial enlarged view of portion 9 in FIG. 1; and, FIG. 10 is a partial enlarged view of portion 10 in FIG. 1. The evenly-spaced broken lines in FIGS. 2 and 8 depict portions of the hanger for clothing care machine that form no part of the claimed design. The dot-dot-dash broken lines in FIGS. 1, 9 and 10 indicate the enlargement areas that form no part of the claimed design.

1 Claim, 10 Drawing Sheets
